[57] CLAIM

The ornamental design for a pet feeding center, as shown and described.

DESCRIPTION

FIG. 1 is a perspective view taken from the top, front and right end of a pet feeding center showing my new design;

FIG. 2 is a top plan view thereof;

FIG. 3 is a rear elevational view thereof;

FIG. 4 is a left end elevational view thereof;
FIG. 5 is a perspective view taken from the top, front and right end of a modified form of the pet feeding center shown in FIG. 1;

FIG. 6 is a top plan view of FIG. 5;

FIG. 7 is a rear elevational view of FIG. 5; and

FIG. 8 is a left end elevational view of FIG. 5.
